UNITED STATES PATENT OFFICE.

HARRY O. RUGH, OF SANDWICH, ILLINOIS, ASSIGNOR, BY MESNE ASSIGNMENTS, TO
HALL SWITCH & SIGNAL COMPANY, A CORPORATION OF MAINE.

CALL-BOX.

1,095,525.

Specification of Letters Patent.

Patented May 5, 1914.

Application filed May 4, 1909. Serial No. 493,940.

To all whom it may concern:

Be it known that I, HARRY O. RUGH, a citizen of the United States, residing at Sandwich, in the county of Dekalb and State of Illinois, have invented a certain new and useful Improvement in Call-Boxes, of which the following is a full, clear, concise, and exact description, reference being had to the accompanying drawings, forming a part of this specification.

My invention relates to calling devices for selective signaling telephone systems, and more particularly to a call box of this kind, and has for its object the provision of a new and improved apparatus of this kind.

In its preferred form, my invention contemplates the provision of means for sending a required number of impulses over a line wire to selectively call one or more of a plurality of stations together, with many incidental functions in the operation of this means, as will be more apparent from its construction, which I will now describe in detail, in connection with the accompanying drawings illustrating one embodiment thereof, in which—

Figure 1 is a diagrammatic arrangement of my improved call box and associated apparatus; Fig. 2 is an open view of my call box; Fig. 3 is a view of the box with the cover closed, portions of the operating devices being broken away; and Fig. 4 is a partially sectional view, more clearly to illustrate the various details involved.

Referring more particularly to Fig. 1, the line circuit over which the impulses are to be sent, is indicated at 1, 2, which, through the interposition of the fuse block 3, connects said line wires to a terminal block 4. The fuse block 3 is of the ordinary type with tubular fuses and a circular lightning arrester, a ground connection being also shown. From this terminal block, the train dispatcher's telephone and signal-receiving circuit is brought out through the conductors 5 and 6.

My improved signal-sending device is adapted to transmit periodic impulses over the line, corresponding to the number of the station to be called to set the various selectors, and after sending the proper impulses to establish a certain circuit condi-

tion, which permits the signal at the substation to operate, whereafter the signal-sending device impresses current on the line 55 to release the various devices at the substations.

Impulses are transmitted over the line wires 1 and 2 from the battery 23, which battery is connected to the two springs 24, 60 which springs are normally in the contact position shown in Fig. 1. When the relay 25 is actuated to draw up said springs 24, the polarity of the battery, as connected to the line conductors 1 and 2, is reversed. 65 This will be more particularly explained later.

Whenever relay 26 is actuated to close circuit through its armature 54, circuit is closed through the conductor 27, through the 70 line wire 1, back over the line wire 2, through conductor 28, upper contact spring 24, battery 23, lower contact spring 24, conductor 74, conductor 29, back to the conductor 27. Thus, for every operation of the 75 relay 26, an impulse is sent over the line wires 1, 2. Now, should the relay 25 be energized temporarily, while the relay 26 is not energized, the reverse battery polarity is transmitted over line conductors 1 and 2, 80 through the agency of conductors 30 and 28.

I will now describe how the relays 25 and 26 are operated to send these various impulses.

My contact-making device consists of a 85 wheel 31, operable by means of a handle 32, and adapted to engage the springs 33 and 34, which are normally not in contact therewith. In starting the mechanism, the handle 32 is made to engage the wheel 31, and 90 to rotate same (referring to Fig. 1) in a contra-clockwise direction, which thereby permits spring 33 to engage a contact strip 35, which closes a circuit that can be traced from said contact spring 33, the conductor 36, key 52, conductor 37, relay 25, conductor 38, conductor 39, through the winding 40, of the polar relay 41, to the frame of the relay 41, through conductor 42, battery 43, conductor 44, element 31, and element 35. 100 This energizes the relay 25, and sends current of what I will call "negative polarity" over the conductors 1 and 2, to release the selective devices at the substations. At the

same time, the coil 40 of the relay 41 repels its armature 45, so that it is not in contact-making position. After the arm 32 has been further swung around, spring 33 breaks 5 with contact element 35, and spring 34 begins to engage element 31, but no contact is established through relays 26 on this account, as circuit is not closed by armature 45. The further actuation of the arm 32, 10 in a contra-clockwise direction, however, electrically connects it with the contact element 46, and thereby a circuit is established through the coil 47, which serves to repel the armature 45 to close circuit with its 15 contact point 48. The armature 45 is pivoted without spring action so that it remains in the position given to it by the last actuation thereof under the influence of either coil 40 or coil 47. The manual actuation 20 of the arm 32 thereupon ceases, and the clockwork mechanism begins to rotate the element 32 in clockwise direction, during which time spring 34 alternately engages teeth 49, thereby intermittently actuating 25 relay 26, as the armature 45 is grounded on the frame of relay 40 until the number of impulses has been completed, and the spring 34 stays in prolonged connection with the element 31, which thereby maintains current 30 upon line conductors 1 and 2, by reason of keeping relay 26 actuated, which is designed to operate the substation signal, all as more clearly explained in my co-pending application, Serial No. 478,088 filed February 15, 35 1909, on which Patent Number 956782 was issued May 3, 1910.

The element 31 maintains contact with the element 34 by engaging the raised portion of the element 31 provided immediately following the teeth and this contact is maintained for an appreciable length of time to actuate the substation signal. A further movement of the element 31 however to its zero position, carries the raised portion of the element 31 beyond the spring 34 to thus again break this contact so that the parts are on open circuit normally.

The circuit through the relay 26 is traced as follows: contact spring 34, relay 26, conductor 50, armature 45, frame of relay 41, battery 43, conductor 44, to the element 31 and its teeth. The actuation of relay 26 thereupon sends positive impulses over line wires 1 and 2, as previously set forth. The arm 32 can be adjustably set with respect to the element 31, thus to vary the number of impulses to be transmitted over line wires 1 and 2, before the contact spring 34 comes into the prolonged circuit connection which 60 operates the local substation signal. After the spring 34 has left the last tooth of element 31 and then broken the prolonged contact therewith, but before the clockwise rotation of the element 31 has been finally 65 completed, the spring 33 again engages con-

tact element 35, which again actuates relay 25, to send a negative impulse over the conductors 1 and 2, to release the substation devices.

It is, of course, necessary, as shown, that the negative impulses be not made coincident with the positive impulses. I provide auxiliary appliances, so that when one station has been called, and I desire to call following stations, this may be done without again operating element 31, and for this reason I have provided a key 51, which is closed with its contact when the element 31 is on its return stroke, and this short-circuits relay 25, and prevents the sending of the negative impulse which would release the local substation stepping devices. This circuit is traced from the lower contact of the push button 51 to the terminal 70 from one conductor of the magnet 25, and from the upper contact of the push button 55, conductor 71 to the conductor 37 of the other terminal of the magnet 25, thus short-circuiting this magnet during its operation. After the element 31 has completed its movement and come to rest, I operate the key 52, which, as will be seen, closes, through the agency of the conductor 53, the same circuit that is ordinarily established by the armature 54, and thereby, I send additional positive impulses to step-up the devices further, or to maintain a given circuit position after a number of impulses have been sent, thereby to call the station desired. This circuit extends from the lower contact of the push button 52 to the line wire 1 by means of the conductor 53 and from the spring 72 of this push button through conductor 73, conductor 74, battery 23, and conductor 28 to the other line wire 2. I further provide a key 55, which, when depressed, actuates the relay 25, to send a negative impulse, thereby to release any substation devices. This circuit extends from the lower contact of the push button 55 through the battery 43, through coil 40, conductor 39, relay 25, and opposite contact of the push button 52 back to the spring 75. This feature is made the subject-matter of a co-pending application, Serial No. 527858, filed Nov. 13, 1909. I have thus described the general circuit conditions and arrangements of my improved call-box and its subsidiary apparatus, and the various instrumentalities of the call box, itself will now be explained by reference to Figs. 2, 3 and 4.

Referring more particularly to Figs. 3 and 4, the handle 32 is provided with a knob 56, which can be inserted in any of the holes 57, thus to regulate the initial movement of the element 31. The box/cover 58 is provided with a stop 59, which is to be engaged by a pin 60, fastened to the wheel 61, which is permanently attached to the element 31, thus to maintain it in its normal or zero 130

position. Thus, in the operation of the device, the handle 56 is placed in any hole 57, and the dial rotated in a clockwise direction (referring to Fig. 3), until the pin 62 engages the stop 46. Then the clock mechanism, consisting of the main spring 63, rotates the elements 31 and 61, in a counter-clockwise direction, until the pin 60 engages the stop 59. I provide a governor, 5 consisting of the weights 64, which regulates the clock mechanism in such a manner as to provide a uniform return movement.

In Fig. 2, the various devices before described are set forth more in detail, a polar 15 relay 41 being mounted within the box 65, and the cover 58 containing the other operating devices.

I show a condenser 69 of special construction to divert foreign currents which tend to 20 act injuriously to telephone service that may be had over the wires 1 and 2. I provide condenser 68 in conjunction with a coil 67, through which impulses caused by the element 54 pass to thereby round out these 25 impulses to minimize their effect on the talking circuit, which may be established around conductors 1 and 2.

While I have herein shown and particularly described the preferred embodiment of 30 my invention, I do not limit myself to the precise construction and arrangement as herein set forth, but

Having thus described my invention, what I claim as new and desire to secure by Letters Patent is:—

1. In a selective call apparatus, the combination of main line terminals, means for impressing impulses constituting a call on said terminals, each call being composed of 40 a given number of impulses, and means whereby a plurality of calls may be made successively by impressing the impulses necessary for the first call on said terminals and subsequently impressing additional impulses so that the sum of the impulses constituting the first call and the additional impulses constitute the successive calls.

2. A selective signal sending device, comprising in combination a movable member, 50 a finger-hold for selectively setting said member to send a call for a predetermined station, an impulse sending device mechanically operated by said member, driving means for automatically restoring said member to normal, a relay for rendering the operations of said impulse device effective or ineffective for signal sending purposes, and means under the control of said member for controlling said relay.

3. A selective signal sending device, comprising in combination a movable member, 60 a finger-hold for selectively setting said member to send a call for a predetermined station, an impulse sending device mechanically operated by said member, driving

means for automatically restoring said member to normal, a governor for regulating the speed of the return movement, a relay for said impulse device to render its operations effective or ineffective, and means under the 70 control of said member for controlling said relay.

4. In a signal sending device, the combination with a movable member, means for selectively setting said member to send a 75 call for a predetermined station, an impulse device under the control of said member, means for controlling the operations of said impulse device to render it effective or ineffective for signal sending purposes, and 80 mechanism under the control of said member for operating said means.

5. A signal sending device, comprising in combination a movable member, means for setting said member to send a call for a 85 predetermined station, an impulse device operated by said member, a relay for controlling the signaling operations of said impulse device to render the same effective or ineffective, and means under the control of 90 said member for controlling said relay.

6. In a signal sending device, the combination with a movable member, a finger-hold for selectively setting said member to send a call for a predetermined station, an impulse sending device mechanically operated by 95 said member, driving mechanism for automatically restoring said member to normal, a governor for regulating the speed of the return movement, a polarized relay 100 for said impulse device, and means under the control of said member for controlling said relay.

7. In a signal sending device, the combination with a movable member, a finger 105 hold for selectively setting said member to send a call for a predetermined station, an impulse sending device operated by said member, a relay for said impulse device, and means under the control of said member for 110 actuating said relay when said member has reached the limit of its forward stroke.

8. In a signal sending device, the combination with a movable member, a finger hold for selectively setting said member to 115 send a call for a predetermined station, an impulse sending device operated by said member, a relay for said impulse device, means under the control of said member for operating said relay when said member has 120 reached the limit of its forward stroke, and means controlled by said member for 125 reversely operating said relay when said member returns to its starting position.

9. In a signal sending device, the combination with a movable member, a finger 125 hold for selectively setting said member to send a call for a predetermined station, an impulse sending device operated by said member, a relay for controlling the signal 130

ing operations of said device, and means under the control of said member for operating said relay when said member returns to its starting position.

- 5 10. In a signal sending device, the combination with a line circuit, of a movable member, a finger hold for selectively setting said member to send a call for a predetermined station, an impulse sending device operated by said member, a relay operated by said impulse device on the return movement of said device to repeat said impulses to the line circuit, driving means for automatically restoring said member to normal, 15 and a governor for regulating the speed of the return movement.

11. In a signal sending device, the combination with a movable member, a finger hold for selectively setting said member to 20 send a call for a predetermined station, an impulse sending device operated by said member on its return movement, driving means for automatically restoring said member to normal, a governor for regulating 25 the speed of the return movement, a pole changer under the control of said member, and a source of current associated with said pole changer.

12. In a signal-sending device, the combination with a movable member, a finger hold for selectively setting said member to send a call for a predetermined station, a signal-setting impulse device operable by 30 said member, a signal-restoring impulse device also operable by said member, and driving means for restoring said member.

13. In a signal-sending device, the combination with a movable member, a finger hold for selectively setting said member to 40 send a call for a predetermined station, a signal setting impulse device operable by said member, a signal-restoring impulse device also operable by said member, said devices operating during the return stroke of 45 said element, and driving means for restoring said member.

14. In a signal-sending device, the combination with a movable member, a finger hold for selectively setting said member to 50 send a call for a predetermined station, a signal-setting impulse device operable by said member, a signal-restoring impulse device also operable by said member, a signal-operating impulse sending device also operable by said member, and driving means for restoring said member.

15. In a signal-sending device, the combination with a movable member, a finger hold for selectively setting said member to 60 send a call for a predetermined station, a signal-setting impulse device also operable by said member, a signal-restoring impulse device also operable by said member, said devices operating during the return stroke 65 of said element, said last-mentioned device

operating also when said member starts its forward stroke, and driving means for restoring said member.

16. In a signal-sending device, the combination with a movable member, a finger hold for selectively setting said member to send a call for a predetermined station, means operable by said member for signal-setting purposes, means operable by said member for signal-operating purposes, 70 means operable by said member for signal-releasing purposes, and driving apparatus for restoring said member.

17. In a signal sending device for signaling substations, the combination with a 80 movable member, means for selectively setting said member to produce signaling impulses for a predetermined station, means operable by said member for operating said signal, means operable by said member for 85 signal operating purposes, and driving apparatus for restoring said member.

18. In a signal-sending device for signaling substations, the combination with a 90 movable member, a finger hold for selectively setting said member to produce calling impulses for a predetermined station, means operable by said member for setting the substation signal, means operable by 95 said member for operating said signal, and driving apparatus for restoring said member.

19. In a signal sending device, the combination with a movable member, means for selectively setting said member to send a call for a predetermined station, electro-magnetically controlled switch element under the control of said means, a circuit for said magnet adapted to be closed when said member has been moved to its limiting forward 105 stroke.

20. In a signal sending device, the combination with main line terminals, of a movable member, means for selectively setting said member to send a call for a predetermined station, an impulse device operated by said member, a relay operated by said impulse device on the return movement of said device to impress said impulses on said line terminals, and driving means for automatically restoring said member to normal. 110

21. In a signal sending device, the combination with a line circuit, of a movable member, means for setting said member to send a call for a predetermined station, an impulse device operated by said member, a relay operated by said impulse device on the return movement of said device to repeat said impulses to the line circuit, and driving means for automatically restoring said member to normal. 115

22. In a signal sending device, the combination with a movable member, means for selectively setting said member to send a call for a predetermined station, an impulse de- 120

vice operated by said member, a relay for said impulse device, and means under the control of said member for actuating said relay when said member has reached the 5 limit of its forward stroke.

23. In a selective call device, the combination of a toothed member having two directions of movement, means for selectively setting said member in one direction to send 10 a call, main line terminals, means whereby an impulse of one polarity is impressed upon said terminals when said member is moved in one direction, means whereby a plurality of impulses of different polarity are impressed upon said terminals when said member 15 is moved in the opposite direction, and means for moving said member back to normal position.

24. In a selective call device, the combination of a movable member, means for selectively setting said member to send a call, main line terminals, a main line relay, a circuit therefor, means for opening the circuit of said main line relay and impressing an 25 impulse of one polarity on said terminals during the setting of said element, and means for closing said circuit and impressing a plurality of impulses of opposite polarity on said terminals during the return movement 30 of said element.

25. In a selective call device, the combination of a movable element, means for setting said element to send a call, main line terminals, means for impressing a plurality 35 of impulses on said terminals of one polarity, and means for impressing an impulse of opposite polarity on said line, said im-

pulses being impressed on said line while said element is moving in one direction.

26. In a selective call mechanism, the combination of a rotatable impulse-sending member, means for setting said member to send a call, a normally open circuit in which 40 said impulses are produced, controlled by said member and adapted to be closed upon 45 said setting means reaching the limit of its setting movement, said movement being different for each call and equal in both directions, and means for opening said circuit when said member returns to normal position. 50

27. In a selective call mechanism, the combination of a rotatable contact member, said member having long and short teeth and being adapted to be moved an equal distance in two directions, means for moving 55 said member to different positions, each position corresponding to a call, a spring contact coöperating with said member, a circuit, the terminals of which are constituted, one by the teeth of said member, and the other by said contact, whereby said circuit is closed when said contact engages said teeth, and a switch in said circuit adapted to be closed when said member is moved in 60 one direction, and opened when said member is moved in the opposite direction. 65

In witness whereof, I hereunto subscribe my name this 19th day of April A. D., 1909.

HARRY O. RUGH.

Corrections in Letters Patent No. 1,095,525.

It is hereby certified that in Letters Patent No. 1,095,525, granted May 5, 1914, upon the application of Harry O. Rugh, of Sandwich, Illinois, for an improvement in "Call-Boxes," errors appear in the printed specification requiring correction as follows: Page 1, line 74, before the word "back" insert the word and reference-numeral *armature 54*; page 4, line 82, for the word "signaling" read *calling*; and that the said Letters Patent should be read with these corrections therein that the same may conform to the record of the case in the Patent Office.

Signed and sealed this 21st day of July, A. D., 1914.

[SEAL.]

R. F. WHITEHEAD,
Acting Commissioner of Patents.
